UNITED STATES PATENT OFFICE.

JULIUS R. FLEMMING, OF YOAKUM, TEXAS.

PAD FOR HORSE-COLLARS.

1,171,709.

Specification of Letters Patent. Patented Feb. 15, 1916.

Application filed February 10, 1914. Serial No. 817,862.

To all whom it may concern:

Be it known that I, JULIUS R. FLEMMING, a citizen of the United States, residing at Yoakum, in the county of Dewitt and State of Texas, have invented new and useful Improvements in Pads for Horse-Collars, of which the following is a specification.

This invention relates to pads for horse collars; and it has for its primary object the provision of a tab of this character which may be connected in the usual well known manner to the tip of one of the side branches of the collar and which will be provided with a free flexible portion formed so as to receive the tip of the other branch of the collar when both branches are adjusted around the neck of the animal whereby the free ends of the pad will be positively held against working from under the collar when excessive pull is applied to the animal at the time of backing.

Another object of the invention is the provision of a pad which may be connected with the collar ends with facility, and one which will be simple, strong and durable, and one which may be connected with the collar without requiring changes in the construction thereof.

With these and other objects in view, the invention consists of certain novel features of construction, combination and arrangement of parts, as will be hereinafter described and claimed.

In the accompanying drawings: Figure 35 1 is a perspective view of a portion of the collar, showing the application of the tab thereto; Fig. 2 is a vertical section therethrough; and Fig. 3 is a perspective view of the pad removed from the collar.

40 The collar 1 herein illustrated is of the usual well known construction and the branch 2 is provided with an adjusting strap 3 of the usual well known form that is adapted to be extended through and adjustably connected with a buckle 4 on the branch 5 of the collar so that both branches of the collar may be held operatively connected with the neck of an animal.

45 The protecting tab which is adapted to span the joint between the tips of the collar branches is constructed from a single strip of leather having a main body portion 7 which underlies the tips of the collar branches at the points of connection thereof, and as shown said body portion is curved

longitudinally and the terminal 8 thereof is secured by stitching or otherwise, as at 9, to the tip of the branch 2. The opposite terminal 10 is extended for a distance beyond the joint between the tips of the collar ends 60 so that it will lie directly against the under sides of the branch 5 near the tip thereof. This terminal 10 is provided with a broadened portion 11, which is upwardly offset from the plane of the body portion 7, and 65 which is separated from the portion 10 by a slot 12, the latter having a length equal to the width of the tip of the branch 5 so that said tip may be properly extended through the passage or slot and the portion 11 then 70 made to overlie the tip as clearly shown in Fig. 1 of the drawings. The sides 13 of the portions 10 and 11 are disposed at the sides of the tip of the branch 5 and incident to the fact that the tip of the branch is extended through the mentioned slot the pad 75 will be positively held against working from its intended position relatively of the tip of the collar branches. The longitudinal sides of the body portion 7 are suitably formed so as to curve up over the sides of the tips of the collar branches and flush therewith whereby to protect the corners of said branches from engaging directly against the 80 neck of the animal.

85 While the pad is preferably constructed of leather, it is to be understood that any suitable well known material may be substituted therefor.

From the foregoing description, taken in 90 connection with the accompanying drawings, the construction and operation of the invention will be readily understood without requiring a more extended explanation.

95 Various changes in the form, proportion, and the minor details of construction may be resorted to without departing from the principle or sacrificing any of the advantages of this invention as claimed.

100 I claim:

105 In a device of the class described, in combination, a harness collar having its opposite ends tapering substantially to a point, connecting elements carried respectively by the ends of said collar and adapted to draw the ends together, a tab consisting of a main body portion having inwardly converging side edges, the connected ends of said collar overlying the inner narrowmost portions of 110 said tab, one of the sides of said tab being

secured fixedly upon the adjacent side of said collar, side portions extending continuously throughout the length of said tab and of such a width as to project beyond the attached ends of said collar and gradually increasing in width toward the ends of said tab, and an offset portion formed upon said tab and located beyond the end of the body portion on one side, the side portions of said

tab continuing beyond said body portion and connected with said offset portion.

In testimony whereof I affix my signature in presence of two witnesses.

JULIUS R. FLEMMING.

Witnesses:

THOS. SMOOT,

GRACE BYMES.
